CLAIM

The ornamental design for a fishing pole scabbard, as shown and described.

DESCRIPTION

FIG. 1 is an isometric top right view of a fishing pole scabbard in a first environment of use showing our new design.

FIG. 2 is a rear elevation view of the fishing pole scabbard of FIG. 1.

FIG. 3 is a right, side elevation view of the fishing pole scabbard of FIG. 1; the left, side elevation view of the fishing pole scabbard of FIG. 1 is the mirror image of FIG. 3.

FIG. 4 is a front elevation view of the fishing pole scabbard of FIG. 1.

FIG. 5 is a top plan view of the fishing pole scabbard of FIG. 1.

FIG. 6 is a bottom plan view of the fishing pole scabbard of FIG. 1.

FIG. 7 is an isometric top right view of a fishing pole scabbard in a second environment of use showing our new design.

FIG. 8 is a right, side elevation view of the fishing pole scabbard of FIG. 7; the left, side elevation view of the fishing pole scabbard of FIG. 7 is the mirror image of FIG. 8.

FIG. 9 is a top plan view of the fishing pole scabbard of FIG. 7; and,

FIG. 10 is a bottom plan view of the fishing pole scabbard of FIG. 7.

The broken lines define the bounds of the claimed design and form no part thereof.
